DESIGN FOR A CONFECTION

John W. West, Maplewood, N. J.

Application September 15, 1933. Serial No. 49,263

Term of patent 14 years

To all whom it may concern:

Be it known that I, JOHN W. WEST, a citizen of the United States and resident of Maplewood, in the county of Essex and State of New Jersey, have invented a new, original, and ornamental Design for a Confection, of which the following is a specification, reference being had to the accompanying drawing forming part thereof. The figure is a view in perspective of a confection showing my new design.

I claim:

The ornamental design for a confection as shown.

Signed at Brooklyn, New York, in the county of Kings and State of New York this 12th day of September A. D. 1933.

JOHN W. WEST.
